DESIGN FOR A SAVINGS BANK

Adelaide E. Wilke, Milwaukee, Wis.

Application February 3, 1948, Serial No. 144,238

Term of patent 14 years

(Cl. D34—11)

To all whom it may concern:

Be it known that I, Adelaide E. Wilke, a citizen of the United States, residing at Milwaukee, in the county of Milwaukee and State of Wisconsin, have invented a new, original, and ornamental Design for a Savings Bank, of which the following is a specification, reference being had to the accompanying drawing, forming part thereof.

Fig. 1 is a view in perspective of a savings bank, showing my new design.

Fig. 2 is a view in front elevation of the same.

Fig. 3 is a view in rear elevation of the same.

I claim:

The ornamental design for a savings bank, as shown.

ADELAIDE E. WILKE.
